US00D528670S

(12) **United States Design Patent** (10) **Patent No.:** **US D528,670 S**
Davina et al. (45) **Date of Patent:** **** Sep. 19, 2006**

(54) **DOOR PANEL**

(75) Inventors: **Glenn A. Davina**, Klamath Falls, OR (US); **Greg Pickens**, Klamath Falls, OR (US); **Stanley K. Meyers**, Klamath Falls, OR (US)

(73) Assignee: **Jeld-Wen, Inc.**, Klamath Falls, OR (US)

(**) Term: **14 Years**

(21) Appl. No.: **29/180,884**

(22) Filed: **Apr. 30, 2003**

(51) LOC (8) Cl. **25-01**

(52) U.S. Cl. **D25/138**

(58) Field of Classification Search D25/48,
D25/138; 52/475.1, 630, 782.1, 784.1

See application file for complete search history.

(57) **CLAIM**

The ornamental design for a door panel, as shown and described.

DESCRIPTION

FIG. 1 is a perspective view of a raised door panel of the present invention. The broken lines are for purposes of showing the environment of a door which form no part of the claimed design; and,

FIG. 2 is a cross-sectional view of the raised door panel along line 2 in the embodiment of the present invention shown in FIG. 1.
